(57) **CLAIM**

The ornamental design for a cup, as shown and described.

DESCRIPTION

FIG. 1 is a perspective view of a cup showing my new design;

FIG. 2 is a front elevational view of the present invention;

FIG. 3 is a rear elevational view of the present invention;

FIG. 4 is a right side elevational view of the present invention;

FIG. 5 is a left side elevational view of the present invention;

FIG. 6 is a top plan view of the present invention; and,

FIG. 7 is a bottom plan view of the present invention.

The broken line showing of environmental structure is for illustrative purposes only, and forms no part of the claimed design.

1 Claim, 7 Drawing Sheets
